UNITED STATES PATENT OFFICE.

JOHN W. McCRONE, OF MULDOON, TEXAS.

LAMP-BURNER.

1,252,709.

Specification of Letters Patent.

Patented Jan. 8, 1918.

Application filed November 14, 1916. Serial No. 131,294.

To all whom it may concern:

Be it known that I, JOHN W. McCRONE, a citizen of the United States, residing at Muldoon, in the county of Fayette and State 5 of Texas, have invented certain new and useful Improvements in Lamp-Burners, of which the following is a specification.

This invention relates to lamp burners.

One of the main objects of the invention 10 is to provide a lamp burner of simple construction and operation having means for supplying air to the lamp flame so as to insure proper combustion and a maximum of light produced by the flame.

15 A further object is to provide means for directing a current of air upward along the wick tube into intimate contact with the flame, such means being provided with devices for maintaining it in proper position 20 relative to the wick tube. A further object is to provide an air conducting and supplying means which may be produced at very small cost and may be quickly and 25 easily applied to a lamp burner of standard construction. Still further objects will appear from the detailed description.

In the drawings:

Figure 1 is a top plan view of a lamp burner constructed in accordance with my 30 invention with the flame cone turned back.

Fig. 2 is a detailed front perspective view of the air conducting casing,

Fig. 3 is an underneath view of the air conducting casing, and

Fig. 4 is a detail plan view of the blank from which the air conducting casing is formed.

The burner is provided with the usual chimney gallery 1 and resilient chimney securing arms 2. The wick tube 3 extends upward above the perforated disk 4 in the usual manner, being positioned at the center of the burner. This tube is formed from a sheet metal blank which is bent into proper shape and has its adjacent edges secured together by a seam or bead-joint 5. The wick may be moved vertically through the wick tube 3 by means of the usual star wheels 6 operated by the wick ratchet 7. The burner so far described is of a standard and well known construction.

Mounted about the wick tube 3 is a sheet metal casing or duct 8. This casing is of approximately elliptical shape and is, when in operative position, concentric with the wick tube. In producing the casing 8 I

first form a blank such as shown in Fig. 4 of the drawings having the central upwardly arched portion 8^a and the two end upwardly arched portions 8^b, and the intermediate downwardly arched portions 8^c, at its upper edge. At its lower edge this blank is provided, at its longitudinal center, with an integral downwardly directed tab 9 having a central rectangular recess 10 and, 65 at each end, with a tab 11. The two tabs 11 are so related that, when the end strips 12 of the blank are secured together by a bent or folded joint, as at 12^a in Fig. 2 of the drawings, they produce a tab diametrically opposite, and similar to, the tab 9, the two recesses 13 being contiguous to form a recess similar to the recess 10. This blank is further provided, a short distance above its lower edge, and at its longitudinal center, 75 with a plurality of spaced apertures 14 and, near each end, with similar apertures 14^a. This blank is bent into the form shown in Figs. 1 and 2 of the drawings, having its adjacent edges secured by a folded joint as 80 at 12^a in Fig. 2. The two opposite tabs at the sides of the casing or duct formed are then turned inward at right angles. These two tabs are of such length as to fit snugly 85 against the side faces of the wick tube, the recess of one of the tabs fitting about the folded joint 5 of the wick tube 3, as in Fig. 1 of the drawings. This serves to secure the air duct in proper adjustment both transversely and longitudinally relatively to the 90 wick tube. A cut or slit is provided in the blank from which casing 8 is formed, adjacent each side of tab 9, and the inner side of each tab 11. By this means, when the tabs are folded inward their underfaces 95 are flush with the lower edge of the casing so that, when the casing is in operative position, its lower edge will rest snugly against the upper face of perforated disk 4. In this position the tabs serve to cover or close the 100 perforations through disk 4 at the sides of the wick tube 3 so as to prevent air from flowing upward through the disk along the sides of the wick tube, the air necessary to cool this tube being supplied through the 105 perforations 14 and 14^a of casing 8.

The air duct or casing 8 causes the air supplied through the perforated disk 4 upon which it rests at each end thereof, to pass upward toward the upper edge of the casing where it flows inward directly and toward the wick tube 3 mixing thoroughly

with the oil vapor from the wick. The result of this mixing of the air and oil vapor by this means is the production of a very brilliant flame of great illuminating power 5 with no increase in oil consumption, on account of the very complete combustion of the oil vapor.

As will be noticed from Fig. 2 of the drawings, the casing has its upper side edges 10 of arcuate shape and curving downwardly toward each end of the casing from the longitudinal center thereof. This results in the ends of the casing being somewhat lower than the center of the casing so that the 15 lamp flame, in its endeavor to extract the maximum amount of oxygen from the air, will tend to spread downward from each end of the wick tube, thus producing a very broad rounded flame having a relatively 20 large surface and capable of producing a large amount of illumination.

A flame cap 16 is hingedly secured to the burner base as at 18. This cap is provided with the usual transversely extending slot 25 19 for the flame and acts to insure a steady and clear flame and to supply air to the flame above the top of the wick, in the usual manner. In normal position this cap is secured over the wick tube 3 and casing 8 30 by means of a spring hook or finger 20 which engages through a slot 21 formed in the burner base.

I am aware that it has been proposed to produce lamp burners having an air duct 35 or casing mounted about the wick tube for supplying air to the flame but, so far as I am aware, it has never been proposed to produce a casing which is detachably mounted about the wick tube and is provided with 40 means engaging with the tube for holding the casing in operative position, this casing being so constructed and shaped as to produce a very broad flame of maximum illuminating capacity.

45 What I claim is:

1. In a lamp burner, the combination of a wick tube provided at the center of one side with a vertically extending seam, and

Copies of this patent may be obtained for five cents each, by addressing the "Commissioner of Patents, Washington, D. C."

a casing mounted about the tube in spaced relation and concentric therewith provided, 50 at the center of the lower edge of each side, with an integral inwardly turned tab having a recess adapted to snugly receive the seam of the wick tube, the upper edge of each side of said casing being of arcuate 55 shape and curving downwardly from the longitudinal center of the casing toward the end of the casing.

2. In a lamp burner, the combination of a wick tube provided at the center of one side 60 with a vertically extending seam, and a casing mounted about the tube in spaced relation and concentric therewith provided, at the center of the lower edge of each side wall, with an integral inwardly extending 65 tab having a recess in its inner end adapted to snugly engage about the seam of the wick tube, the casing being further provided with a plurality of spaced apertures in each side and having the upper edge of each side wall 70 of arcuate shape and curved downwardly from the longitudinal center of the casing toward each end of the casing.

3. An attachment for lamp burners comprising a casing adapted to be mounted in 75 concentric space relation to a wick tube having at the center of the lower edge of each side wall an inwardly extending tab provided with a recess in its inner end adapted to snugly receive the seam of a wick tube, 80 the under faces of said tabs being flush with the lower edge of the casing whereby the lower end of said casing will rest directly on the gallery of a lamp burner when in operative position, said casing having the 85 upper edge of each side wall of arcuate shape and curved downwardly from the longitudinal center toward each end of the casing.

In testimony whereof I affix my signature 90 in presence of two witnesses.

JOHN W. McCRONE.
